UNITED STATES PATENT OFFICE.

CHARLES AUBREY BUCKLIN, OF NEW YORK, N. Y., ASSIGNOR TO JOHN S. SPENCER, OF SAME PLACE, AND JAMES E. SPENCER, OF BROOKLYN, N. Y.

OPHTHALMOSCOPIC TEST-LENS.

SPECIFICATION forming part of Letters Patent No. 308,302, dated November 18, 1884.

Application filed March 13, 1884. (No model.)

To all whom it may concern:

Be it known that I, CHARLES AUBREY BUCKLIN, a citizen of the United States, and a resident of New York, in the county of New York and State of New York, have invented certain new and useful Improvements in Ophthalmoscopic Test Lenses, of which the following is a specification.

The invention relates to improvements in ophthalmoscopic test-lenses; and its nature and method of use will be fully understood from the detailed description hereinafter presented, reference being had to the accompanying drawings, in which—

15 Figure 1 is a front elevation of an apparatus embodying the elements of the invention. Fig. 2 is a central longitudinal section of same on the line *x x* of Fig. 1. Fig. 3 is a detached view of that portion of the apparatus used for 20 determining the pupillary distance between the eyes. Figs. 4, 5, and 6 are detached views of the disks *V*, *W*, and *X*; and Figs. 7 and 8 are detached views of parts which will be understood by the reference thereto by letters 25 hereinafter.

Referring to the drawings, *A* denotes a stand, which will preferably be of cast-iron and of ornamental configuration, and its use is simply to support the bifurcated standard 30 *B* and to permit the vertical adjustment of same. The lower portion of the standard *B* enters the frame or stand *A*, and when elevated to any desired position it is there retained by the clamping-ring *C* and set-screw 35 *D*, which ring encircles the standard and rests upon the upper end of the frame *A*. Above the ring *C* the bifurcated standard *B* has an enlargement, *E*, from the front and rear edge of which its two arms, lettered *F G*, respectively, extend upward a proper distance, tapering in width, preferably, toward their upper end, where they are provided with corresponding bearing-apertures *H I*. The front arm, *F*, of the standard *B* has near its base 40 an elongated opening, *J*, and index-fingers *K L*, one finger being at the upper and the other at the lower edge of the opening *J*, and the purposes of which will be mentioned hereinafter.

Between the arms *F G* of the standard *B* is 45 mounted upon the hollow hubs *M N* the hol-

low disk *O*, the hubs *M N* passing through the apertures *H I* into corresponding apertures provided in the anterior and posterior sides of the disk. The hub *M* has an outwardly-deflecting flange on its front edge, 55 which adapts it for an eye-piece, and through these hubs and the hollow disk is the line-sight for the apparatus. The posterior face of the disk *O* will preferably be secured in place by small screws, and the disk is adapted 60 to revolve upon the bearings afforded by the hollow hubs *M N*.

Upon the anterior face of the disk *O* are supplied the openings, lettered *P Q R*, respectively, one being at each side and slightly 65 above its longitudinal center when in a normal position, the other being at its upper portion, as indicated, and upon the lower semi-circumference of the said face of the disk is arranged a scale of degrees, *S*, having above 70 and below it the proper indicating figures, those above the scale commencing from 0 at the opening *P* and increasing to 180 at the opening *R*, while those figures below the scale commence at 90 adjacent to the opening *P*, as 75 ascending to 180 at the vertical center of the disk and thence beginning at 0 and increasing to 90 at the opening *R*. The application of the scale numbered as described and shown is rendered desirable from the fact that the position 80 of the axis in which convex cylindrical lenses are usually required by the eye is 90, while the position in which concave cylindrical lenses is thus required is 180. The row of figures above the scale will therefore be understood to indicate the position of the convex cylindrical lenses, while those below the scale indicate the axes of the concave cylindrical lenses herein- 85 after described. The purpose of the scale *S* will be explained hereinafter in connection 90 with the parts of the apparatus which co-operate therewith.

Within the hollow disk *O* are mounted upon horizontal pins the smaller disks, lettered *V W X*, one being above and one upon each 95 side of the axis of the disk *O*. The margin of each of the disks *V W X* is provided with a row of perforations, *a*, which are equidistant from each other, and are arranged on a line concentric with the axis of the disk. In the 100

apertures *a* in the disk X are provided thirteen convex cylindrical lenses, whose axes stand at 90° of the universal standard used in indicating the axes of cylindrical lenses, 5 and thirteen concave cylindrical lenses, the axis of each of which is set at 180° of the normal standard. The disk V has secured in its row of perforations a twenty-nine convex lenses, and the disk W is similarly provided with an equal number of concave lenses. 10 In each of the disks V W X one of the apertures is left blank—that is, it contains no lens. The size and arrangement of the disks V W X are such that they project slightly beyond the periphery of the disk O, as shown, and that the rows of perforations *a*, when the disks are rotated, cross each other's path directly on the line of sight through the hollow hubs M N. The purpose of having the edge 15 of the disks V W X project beyond the edge of the disk O is to permit them to be conveniently rotated by hand, when desired, and of the arrangement of the apertures *a* described is to bring any desired combination of lenses 20 25 behind the eye-piece during the operation of testing the eye.

Upon the rotation of the disks V W X the strength of the lenses brought within the line of sight will be indicated by the numbers 30 formed upon the disks in circular lines, and arranged to appear at the openings P Q R, hereinafter mentioned—that is to say, the strength of the lens brought by the disk V before the hub M will be denoted by the appropriate figure at the opening P, that by the disk W by a figure at the opening R, and that by the disk X at the opening Q.

When the disk V is rotated downward, for illustration, it will bring at the eye-piece M, in 40 constantly-increasing strength, (commencing at 0,) twenty-nine concave lenses, whose strength will be indicated to the observer by the figures regularly appearing before the opening V. The same is true of the disk W, except that the strength of the lenses in this disk 45 is indicated by the figures appearing at the opening R.

When the disk X is revolved toward the right, (from 0,) it will bring its thirteen convex cylindrical lenses before the eye-piece M in regular order, their strength being denoted by figures and the sign + at the opening Q, and when the disk X is revolved toward the left (from 0) its thirteen concave cylindrical 55 lenses will appear before the eye-piece M, while their strength will be indicated by the numbers and the sign — at the opening Q. The openings P Q R are provided with inwardly-tapered flanges Y, which extend to a 60 point adjacent to the faces of the disks V W X, and their purpose is to direct the vision to the characters appearing on the disks in rear of the openings, and to avoid the disclosure of any character to view, except such as is directly behind the opening.

The disks V W X will be prevented from

rotating, except when positively moved by hand, by springs *c*, which will exert a constant pressure against them, but will not prevent their being rotated when desired.

A spring-pawl, *d*, having a padded bearing-point, *e*, is provided for the purpose of preventing the too free rotation of the large disk O, and to detain it in any set position until moved by hand. This pawl will be secured to the arm G, and its end will impinge the posterior face of the disk O. The pawl *d* is shown in a detached view in the drawings, and in said view the point of the pawl is indicated by dotted lines, the encompassing full lines 80 describing the outline of the padded portion. A pawl of any suitable description may be employed for the purpose of restraining the movement of the large disk. The shank end of the pawl *d* will be secured to the adjacent 85 standard by a rivet or otherwise, the section in Fig. 2 being on a line which prevents the rivet being shown. I shall prefer to polish the surface of the disk O in a circle corresponding with the path described by the padded end of the pawl *d* as the disk is rotated. 90

Upon the rear portion of the standard B is secured a bracket, *f*, to which is applied an arm, *g*, which will have upon its face the usual graduated scale, and will carry a suitable slide, 95 *h*, to hold a reading-tablet of the customary kind used in testing eyes. The inner bent end of the arm *g* enters an aperture in the bracket *f*, from which it may be removed at will.

In testing the eyes preparatory to selecting a suitable pair of glasses it is necessary, among other things, to determine the distance between the pupils, and to accomplish this I have produced the device illustrated in Fig. 3, which when in use may be introduced into 100 the socket formed in the bracket *f*, the arm *g* having been previously removed. The said device illustrated in Fig. 3 consists of the standard *m* supporting a cross-bar, *n*, upon which a graduated scale is provided and which 110 carries two disks *t u*. These disks may both be adjustable toward or from each other, or one may be fixed and the other movable. In each of the disks *t u* a vertical slit, *w*, is 115 formed, and within one of them, preferably the one at the left, a prism, *x*, covers the slit. In the use of this part of the invention the left disk *t* is brought against the left eye and the right-hand disk then moved on the bar *n* until its slit *w* is directly in front of the pupil 120 of the right eye, at which time the person will see double, and by observing the scale on the bar the pupillary distance may be at once determined. The object to be looked at through the disks *t u* should be about ten feet from the 125 instrument.

In the employment of the apparatus hereinbefore described any single lens or combination of lenses desired may be brought before the eye-piece M, as will be readily understood. 130 When a single lens of any one disk is to be used at the eye-piece, blank apertures in the

other two disks will be turned in line with the lens in use.

The scale S is only to be employed in connection with the disk X, which contains, as aforesaid, a series of concave and a series of convex cylindrical lenses. The axes of the concave cylindrical lenses will be automatically indicated on the outer row of scale figures by the index-point L, while the axis of the convex cylindrical lenses will be similarly denoted by the index-finger K. The axis of the cylindrical lenses may be placed in any desired angle to suit the eye, being tested by rotating the large frame or disk, and when such angle has been reached it will be denoted on the scale S by the fingers K or L, and the optician will accordingly be enabled to prepare a glass the axis of which will suit the eye tested.

20 What I claim as my invention, and desire to secure by Letters Patent, is—

1. In apparatus for testing the eyes, a disk having a line of sight through its center, in combination with smaller disks carrying a series of lenses and indicating-characters, which lenses, when the smaller disks are rotated, may be brought before the sight-line, substantially as set forth.

2. The disk O, having a line of sight through it, and openings P Q R, in combination with the disks V W X, carrying a series of lenses, and which, when rotated, cause said lenses to cross the sight-line, the character of the lenses on the line of sight being denoted at the one or more of the openings, P Q R, substantially as set forth.

3. The hollow disk O, inclosing the smaller disks, with their lenses and indicating-characters, and having a line of sight across which the lenses may pass when the smaller disks are rotated, and openings through which said indicating characters may be observed, substantially as set forth.

4. The combination, with the disk O, having a sight-line through it, and openings P Q R, of the disks V W X, one whereof containing a series of convex spherical lenses, another a series of concave spherical lenses, and a third a series of both concave and convex cylindrical lenses, the relation of the disks being such that when rotated their lenses will cross the line of sight and their strength be indicated at the openings P Q R, respectively, substantially as set forth.

5. In eye-testing apparatus, the disk X, carrying a series of concave and convex cylindrical lenses, in combination with the frame O, having a line of sight properly arranged with relation to the lenses, and provided with a scale, S, substantially as and for the purposes set forth.

driical lenses, in combination with the frame O, having a line of sight properly arranged with relation to the lenses, and provided with a scale, S, substantially as and for the purposes set forth.

6. In eye-testing apparatus, the frame O, provided with the scale S, as described, and mounted upon hollow hubs or bearings M N, in combination with the disk X, carrying a series of convex and concave lenses properly arranged to be brought behind the hollow hub M when desired, the strength of the lens being indicated at the opening Q, and its axis on the scale S by the finger K or L, substantially as set forth.

7. The disk O, provided with the openings P Q R, and scale S, and mounted upon hollow bearings in the frame B, having index-points K L, in combination with the disks V W X, carrying lenses, and arranged to bring the same when rotated behind the hollow front bearing, substantially as set forth.

8. For use in combination with apparatus for testing the eyes preparatory to selecting a suitable pair of glasses, the disks t u, having a vertical slit, w, and arranged upon an arm having a scale, substantially as and for the purposes specified.

9. For use in combination with apparatus for testing the eyes preparatory to selecting a suitable pair of glasses, the disks t u, having each a vertical slit, w, and arranged upon a bar provided with a scale, one of the disks containing a prism arranged over the slit, substantially as set forth.

10. In eye-testing apparatus, the disk O, provided with openings P Q R, having flanges Y, in combination with the lens-carrying disks V W X, and hollow hubs M N, substantially as set forth.

11. In eye-testing apparatus, the disk O, mounted upon hubs M N, and inclosing smaller rotating disks carrying lenses, in combination with the bifurcated frame B and friction-pad d, substantially as and for the purposes set forth.

12. The rotating disk O, having a scale, S, and carrying a smaller disk provided with a series of lenses, the axis of which is denoted by the scale, substantially as set forth.

Signed at New York, in the county of New York and State of New York, this 10th day of March, A. D. 1884.

CHARLES AUBREY BUCKLIN.
